AUTOMATIC DISCHARGE APPLICATOR FOR
DISPENSING CONTAINERS

Russell B. Kingman, Orange, N. J.

Application January 24, 1940, Serial No. 315,356

2 Claims. (Cl. 15—139)

This invention relates to improvements in dispensing containers equipped with discharge applicator means through which the content of the container may be emitted and by which it may be operatively applied to an area desired to be treated thereby; and the invention has reference, more particularly, to a novel construction of automatic discharge applicator which is normally closed against emission of the container content, but which opens under pressure incident to operative use thereof as an applicator means.

This invention has for an object to provide a novel automatic discharge applicator for a dispensing container in the form of a closure means for connection with the mouth of the container, and which is provided externally with a suitably supported pervious applicator member, cooperatively combined with which are a plurality of normally closed valved vents adapted to be opened, in whole or in part, in response to pressure, of the whole or selected areas of the applicator member against a surface to which the latter is applied in use; with the result that the emitted content of the container is directed or fed to only that portion of the applicator member which is in use in a given case, and only that quantity of said content is dispensed which is required in such case, whereby said content is efficiently conserved against waste.

The invention has for another object to provide a novel automatic discharge applicator, of the kind and for the purposes stated, which is self-sealing when not in use, to the end that the container content is further conserved against waste by evaporation or other dissipation.

The invention has for a further object to provide a novel automatic discharge applicator generally useful for dispensing fluent substances, such e. g. as liquids, siftable powders, and the like.

Other objects of this invention, not at this time more particularly enumerated, will be understood from the following detailed description of the same.

Illustrative embodiments of the instant invention are shown in the accompanying drawings, in which:

Fig. 1 is a longitudinal vertical sectional view of a dispensing container equipped with one illustrative embodiment of automatic discharge applicator according to this invention, the same being shown in its normally closed, self-sealing condition; Fig. 2 is a top end view of said automatic discharge applicator equipped container, parts being successively broken away to disclose

underlying structure; Fig. 3 is a fragmentary vertical sectional view similar to that of Fig. 1, showing but a portion of the discharge applicator area applied for use, with consequent partial and proportionate opening of the valved vents for emission of the container content; and Fig. 4 is a view similar to that of Fig. 3 but showing the whole available area of the discharge applicator in use with consequent open condition of all of the valved vents.

Fig. 5 is a fragmentary vertical sectional view of a modified embodiment of the discharge applicator means; and Fig. 6 is a top plan view thereof, with portions of the applicator member broken away.

Fig. 7 is also a fragmentary vertical sectional view of another modified embodiment of the discharge applicator means; and Fig. 8 is a top plan view thereof, with parts successively broken away to disclose underlying structure.

Fig. 9 is a fragmentary vertical sectional view showing still another modified embodiment of the discharge applicator means.

Similar characters of reference are employed in the above described views, to indicate corresponding parts.

In the drawings, the reference character 1 indicates a container for holding a supply of fluent material desired to be dispensed; illustratively said material may, e. g., be a liquid cleaning fluid such as commonly used for removing soil spots from garments and other materials. It will be understood, however, that any fluent material, capable of passing from the container interior to and through the pervious material of the applicator member later described, may be dispensed from the container. Said container 1 is illustratively shown in the form of a glass bottle or jar, but it will be obvious that the same may comprise a can, box, or other receptacle form which may be made of metal, paper, plastics or any other desired suitable material.

The discharge applicator means, in the embodiment thereof shown in Figs. 1 to 4 inclusive, 45 comprises a metallic shell or ferrule 2, illustratively shown as having at its lower end a screw-threaded portion 3 to screw onto the externally threaded neck of the container 1, to thereby operatively attach the discharge applicator means 50 to the latter. It will be understood, however, that any other form of connection of the discharge applicator to the container may be resorted to. If, for example, the container 1 is in the form of a can, said shell or ferrule 2 might well be formed as an integral part thereof. At

its upper end, said shell or ferrule 2 is provided with an outwardly and upwardly inclined or flared rim section 4. Disposed to lie across and to close the open top of said shell or ferrule 2 is a top plate 5 which is provided, about its periphery, with a dependent inwardly and downwardly inclined or flared clamp flange 6 adapted to extend externally about and to cooperate with said flared rim section 4 of the shell or ferrule 2. The applicator member 7 is arranged to overlie said plate 5 in such manner that its outlying portions extend downwardly over the exterior of the clamp flange 6, being thereupon upturned so that its marginal portions 8 extend upwardly over the interior face of said clamp flange 6. Preferably, a padding 9 of felt, cotton wool, or any other suitable material adapted to provide a resilient, pervious mass 15, interposed between the applicator member 7 and said plate 5. In some cases, and especially when an applicator member of substantial body is employed, said padding 9 may be omitted. The applicator member 7 may be made of any suitable flexible pervious material, fabric or the like. Preferably a pile fabric is employed. When the applicator for dispensing and applying a liquid fluid for cleaning or similar operations, it has been found most advantageous to employ a pile fabric having a comparatively stiff brush-like pile, such e. g. as a mohair fabric.

When the applicator member 7 has been assembled, with or without the interposed padding 9, upon the plate 5 in the manner above described, the assembly is sprung over the flared rim section 4 of the shell or ferrule 2, so as to clamp the marginal portions 8 of the applicator member between said rim section 4 and the clamp flange 6 of plate 5, thus not only securing the applicator member 7 in place, but also engaging the plate 5 in operative secured assembled relation to the shell or ferrule 2. Affixed to the underside of the plate 5 is a gasket member or packing sheet 10 of soft, resilient and moisture proof material; such e. g. as rubber or material of equivalent qualities. Preferably, the outer marginal portions of said gasket member or packing sheet 10 extend between the top of the shell or ferrule rim section 4 and the plate 5, so as to seal the joint therebetween against leakage.

The valved vents of the discharge applicator means, in one illustrative form thereof as shown in Figs. 1 to 4 inclusive, are provided in connection with the top plate 5, and comprise a plurality of valve ports 11 extending through said plate 5 and said gasket member 10 which faces the underside thereof. These ports 11 are disposed circumferentially in spaced relation around the area of the plate 5, preferably so as to form circular rows thereof, one such row being located adjacent to the outer perimeter of the applicator member 7, and the other row somewhat inwardly of said first mentioned row, and also in such relative arrangement that the ports of one row are in staggered relation to the ports of the other row. Of course, other dispositional arrangement and spacings of the plurality of ports 11 may be resorted to if desired. Cooperative with each port 11 is a valve disk 12 which abuts the gasket member faced side of the plate 5 so as to normally close and seal the port. Each valve disk 12 is provided with an upwardly projecting axial stud 13 of less diameter than the port 11, and arranged to project beyond the exterior side of the latter. Each valve disk 12 is independently yieldably pressed to normal port

closing position. For this purpose a spider form spring member is provided, the same having a central portion 14 centrally affixed to the underside of the plate 5, as by welding the same thereto or by any other suitable means of mechanical connection. Radiating from said central portion 14 are spring arms 15 leading to each valve disk 12, the latter being preferably but not necessarily affixed to the extremities of said arms. Said spring arms may be of either bowed or straight formation.

Illustrative of the use and operation of the discharge applicator means above described, it will be assumed that the container 1 holds a liquid cleaning fluid or spot remover liquid. When the container 1 normally stands on its base, or is otherwise positioned but without subjecting the applicator means to pressure, the valve disks 12 will occupy their port closing positions (see Fig. 1), thus closing and sealing the ports against discharge of the liquid therethrough, or of reduction of the liquid by evaporation. When use of the device is desired, the container is inverted, and the applicator member 7 is applied to the material M desired to be cleaned. If the spot to be removed is of small area, but a limited area of the applicator member 7 need be pressed against the spotted portion of the material M. This is done by somewhat inclining or tilting the container (see Fig. 3). Under such circumstances only a limited area of the applicator member 7 is subjected to pressure, so that such pressure is transmitted only to those valve disk studs 13 which lie in the area of such pressure. As a consequence of this but a limited outflow of cleaning liquid is discharged, and that is directed toward only that much of the area of the applicator member 7 which is in contact with the material. It will be obvious, therefore, that the liquid is thus conserved against waste, and only so much thereof is discharged as is required for the limited cleaning treatment involved. If, however, the area of material to be cleaned is large, and consequently the entire area of the applicator member 7 is required to be brought into use, then said entire area of the latter is contacted with and pressed against the material M, with the result that such pressure is transmitted to all valve disk studs 13 so that all valve disks 12 are forced open. Under such circumstances, a maximum discharge of cleaning liquid is attained so as to adequately saturate the entire applicator member body (see Fig. 4). It will therefore be understood that, by the automatic action induced by pressure of greater or less areas of the applicator member 7 to the work, a greater or less quantity of cleaning liquid will be discharged both proportionate to and directed or lead to that portion of the applicator member which is at work.

In Figs. 5 and 6 there is shown a somewhat modified arrangement of the discharge applicator means structure, which, however, functions in the same manner and with the same advantages as already set forth. In this arrangement, the spider form spring member is attached to the upper or outer face of the plate 5 by its central portion 14 so that its radial spring arms 15' flex outwardly against and so as to normally outwardly distend the applicator member 7. The valve disks 12 are interconnected with the ends of the spring arms 15' by means of draw pins or links 13', whereby outward flexing of said spring arms 15' normally draws and holds said

valve disks 12 in port closing position, subject to opening when said spring arms 15' are inwardly flexed under pressure applied to the applicator member.

In Figs. 7 and 8 there is shown another and somewhat simplified form of discharge applicator means which, however, embodies the general principles of this invention. In this arrangement, underlying the plate 5 having the ports 11 is a single valve plate or disk 16, normally upwardly and yieldably pressed against the gasket faced underside of said plate 5 in port closing relation thereto. Said valve plate or disk 16 is yieldably thrust to such position by an underlying bowed spring member 16' which is footed by its ends against the walls of the shell or ferrule 2. Underlying the applicator member 7 is a perforate pressure responsive member or plate 17, which is normally spaced above the top plate 5, and which is provided with a central dependent stud 18 adapted to extend through a central opening 19 in said plate 5 so as to engage said valve plate or disk 16. It will be obvious that, when pressure is applied to a marginal area of the applicator member 7, such pressure will be transmitted through the member or plate 17 and its stud 18 to the valve plate or disk 16 so as to tilt the same and thereby open ports 11 immediately adjacent to the area of pressure thus applied to the applicator member 7. In such case the cleaning liquid will discharge through the thus opened ports 11, and thence through the adjacent perforations of the member or plate 17, to the area of the applicator member 7 which is at work. On the other hand if pressure is exerted through the entire area of the applicator member 7, i. e. perpendicular to its face plane, the valve plate or disk 16 will be bodily moved axially so as to open all ports 11 of plate 5 to the discharge of the cleaning liquid to the applicator member 7.

In Fig. 9 there is shown still another modified form of discharge applicator means, wherein is provided an upwardly open, hollow, stationary female valve member 20, the annular side walls 21 of which are provided with a circumferential row of ports 22. This female valve member 20 may be formed either as an integral part of the shell or ferrule 2 (as shown), or as an integral part of the flanged plate 5. If made in the former manner, said plate 5 is centrally cut away to expose the upwardly open side of said female valve member. Cooperative with said female valve member 20 is an upwardly open, hollow, movable male valve member 23, the annular side walls 24 of which are provided with a circumferential row of ports 25 corresponding to those of the female valve member. The walls 24 of the male valve member slidingly interfit within the walls 21 of the female valve member. About and from the upper margins of the walls of the male valve member extends a lateral flange 26 to underlie the applicator member 7. Arranged between the bottom of the female valve member 20 and the male valve member 23 is a bowed or other suitable form of spring 27 which yieldably thrusts the male valve member outwardly relative to the female valve member so

that the respective ports 22 and 25 are disposed out of register, and consequently closed against outflow of liquid, while at the same time the up-thrust of said male valve member also operates to distend the applicator member 7. If desired, the interior of the male valve member 23 may be filled with fibrous or like material, such as cotton, wool or the like. It will be obvious that, when pressure is applied to the applicator member inward movement of the male valve member 23 relative to the female valve member 20 is induced, whereby the valve ports 22 and 25 are brought into partial or complete registration thus controlling quantity emission of liquid accordingly.

Since many changes could be made, and widely different embodiments of the features of this invention could be made without departing from the scope thereof as defined in the following claims, it is intended that all matter contained in the above description or shown in the accompanying drawings shall be interpreted as illustrative and not in a limiting sense.

I claim:

25 1. In combination with a container for dispensing fluent material, a discharge applicator means connected with the open end of said container comprising, an external pervious applicator member, a top plate intermediate said applicator member and the end opening of said container, said top plate having a plurality of vents spaced around the marginal portions thereof to respectively underlie different areas of said applicator member, a closure valve for each said vent opening, spring means having radial arms for the respective valves to yieldably and independently hold the same in vent closing position, and means connected with each valve responsive to pressure exerted upon said applicator member 40 whereby to open one or more up to all of said valves accordingly as pressure is applied to selected areas or the entire area of said applicator member.

2. In combination with a container for dispensing fluent material, a discharge applicator means connected with the open end of said container comprising, an external pervious applicator member, a top plate intermediate said applicator member and the end opening of said container, said top plate having a plurality of vents respectively underlying different areas of said applicator member, resilient gasket means on the underside of said top plate bordering each vent, a closure valve for each said vent cooperative with the gasket bordered side thereof, a spider form spring member affixed to said top plate having radial spring arms respectively engaging the respective valves to yieldably and independently hold the same in vent closing position, and each valve having a pressure transmission stud upwardly projecting through the corresponding vent so as to be responsive to pressure exerted upon said applicator member whereby to open one or more up to all of said 65 valves accordingly as pressure is applied to selected areas or the entire area of said applicator member.

RUSSELL B. KINGMAN.
